(57) **CLAIM**

The ornamental design for a garment with closure, as shown and described.

DESCRIPTION

FIG. 1 is a front perspective view of a garment with closure showing my new design in a closed configuration.

FIG. 2 is a front view of my new design shown in FIG. 1.

FIG. 3 is a rear view of my new design shown in FIG. 1.

FIG. 4 is a right-side view of my new design shown in FIG. 1. The left-side view is a mirror image thereof.

FIG. 5 is a top view of my new design shown in FIG. 1.

FIG. 6 is a bottom view of my new design shown in FIG. 1.

FIG. 7 is an enlarged detail of the encircled portion 7 shown in FIG. 1.

FIG. 8 is a front perspective view of my new design shown in FIG. 1 in an open configuration.

FIG. 9 is a front view of my new design shown in FIG. 8.

FIG. 10 is a rear view of my new design shown in FIG. 8.

FIG. 11 is a right-side view of my new design shown in FIG. 8. The left-side view is a mirror image thereof.

FIG. 12 is a top view of my new design shown in FIG. 8.

FIG. 13 is bottom view of my new design shown in FIG. 8; and,

FIG. 14 is an enlarged detail of the encircled portion 14 shown in FIG. 8.

The portions of the garment with closure shown in short broken lines form no part of the claimed design.

The portions of the garment with closure shown in long broken lines are stitching and are not part of the claimed design.

The dot-dash broken lines on the garment with closure are boundary lines that show the claim design extends to, but does not include the boundary line. The dot-dash broken line circle shown in FIGS. 1 and 8 show the portion of the design that is shown enlarged in FIGS. 7 and 14, respectively.
